UNITED STATES PATENT OFFICE.

SIGMUND STERNAU, OF NEW YORK, N. Y.

DESIGN FOR AN ALCOHOL-LAMP.

SPECIFICATION forming part of Design No. 23,552, dated August 7, 1894.

Application filed March 19, 1894. Serial No. 504,323. Term of patent 3½ years.

To all whom it may concern:

Be it known that I, SIGMUND STERNAU, a citizen of the United States, residing in New York, county of New York, and State of New York, have invented and produced a new and original Design for an Alcohol-Lamp, of which the following is a specification, reference being had to the accompanying drawings, in which—

10 Figure 1 is a view in perspective, showing my newly designed lamp. Fig. 2 is a side view thereof.

15 The design consists of a lamp A, the body or bowl B of which is extremely wide and flat in comparison with its height, the lower portion

of the said body B passing by an ogee curve into and terminating in a relatively narrow and flat base C. From the body or bowl extends a spout D, and to the top is secured the curved handle E.

20 F represents the lid of the lamp provided with a handle G.

What I claim is—

The design for an alcohol lamp as hereinabove shown and described.

SIGMUND STERNAU.
